HUBCAP

Richard E. Dieterich, Long Beach, Ind.

Application March 3, 1953, Serial No. 23,869

Term of patent 14 years

(Cl. D14—30)

To all whom it may concern:

Be it known that I, Richard E. Dieterich, a citizen of the United States, residing at Long Beach, State of Indiana, have invented a new, original, and ornamental Design for a Hubcap, of which the following is a specification, reference being had to the accompanying drawing, forming a part thereof.

Fig. 1 is a front elevational view of a hubcap embodying my new design.

Fig. 2 is a perspective view of the same.

Fig. 3 is a sectional through the same taken along the line 3—3 of Fig. 1 and in the direction indicated.

The dotted line disclosure of wheel spokes is shown only for the purpose of illustration.

I claim:

The ornamental design for a hubcap, as shown and described.

RICHARD E. DIETERICH.
